ATTORNEY

UNITED STATES PATENT OFFICE.

ARTHUR MAYBREY NICHOLS, OF AUBURN, VICTORIA, AUSTRALIA.

MACHINE FOR LABELING CYLINDRICAL TINS AND THE LIKE.

1,355,563.

Specification of Letters Patent.

Patented Oct. 12, 1920.

Application filed May 17, 1919. Serial No. 297,878.

To all whom it may concern:

Be it known that I, ARTHUR MAYBREY NICHOLS, a subject of the King of Great Britain, residing at No. 61 Lingwell road, 5 Auburn, in the State of Victoria and Commonwealth of Australia, have invented an Improved Machine for Labeling Cylindrical Tins and the like, of which the following is a specification.

10 This invention of an improved machine for labeling cylindrical tins and the like, consists essentially in the combination with a semi-circular way, to one end of which the cylindrical tins, cartons, or other containers, 15 (hereinafter referred to as "containers"), are fed, of a rotary device situated above and in alinement with said semi-circular way, for the purpose of causing said containers to revolve along said way, during 20 the process of labeling, and be delivered at the other end of said way, when the labeling thereof has been effected.

Referring to the drawings hereto annexed in which the same reference numerals indicate the same parts wherever they occur:

25 Figure 1 is a front elevation partly in section of my improved machine.

Fig. 2 is a side elevation of same also partly in section.

30 Fig. 3 is partly a plan and partly a sectional view of the upper part of the machine taken on the line *a b* Figs. 1 and 2.

Fig. 4 is a plan view of the lower part of the machine taken on the line *c. d.* Fig. 1.

35 Fig. 5 is a front elevation of the means for applying gum to the containers to admit of their picking up one end of the label to be attached thereto; and

Fig. 6 is a cross sectional view on the line 40 *e. f.* Fig. 1.

Fig. 7 is an end elevation of the threaded tapered split compression bush on axle 3, by the aid of which bush the space between the wheels 1 and 2 can be adjusted.

45 Fig. 8 is a part section and part side elevation of the adjusting gear, shown in Fig. 7, in which the relative positions of the wheels 1 and 2 and tapered split compression bush are indicated.

50 Fig. 9 is an end elevation of paste receptacle 34, showing the means for driving the paste band pulley.

1 and 2 are wheels constituting the rotary device for revolving the containers to be 55 labeled along the semi-circular way herein-after described. Said wheels are carried on

horizontal axle 3 which latter is free to revolve in suitable ball bearings 4 and 5, bearing 4 being situated at the top of the pedestal 6, and bearing 5 being situated at the 60 top end of a bracket 7 (see Fig. 2) projecting upwardly from said pedestal 6. The periphery of each of said wheels 1 and 2 consists of a series of steps 8 which extend inwardly from the outside to the inside there- 65 of, and constitute flanges for engagement with the top and bottom edges of the container 9 during the operation of labeling.

10 and 11 are wheels each of which engages with a right hand screw thread, and 70 threaded tapered split compression bush on said axle 3. By revolving said wheels 10 and 11 to the left, the wheels 1 and 2 are loosened on said axle 3 and may be moved either outward or inward on said axle 3. 75 To refasten wheels 1 and 2 on said axle 3 said wheels 10 and 11 are turned to the right. By this means the width between 80 wheels 1 and 2 can be increased or decreased so as to admit of the flanges thereof engag- 85 ing with the top and bottom edges of containers of varying size.

12 and 13 are fast and loose pulleys on horizontal axle 3 through which motion is transmitted by belting from any suitable 85 source of power. 14 is the semi-circular way along which the containers are revolved during the process of labeling. This semi-circular way consists of two side pieces each being formed at its bottom with an in- 90 wardly projecting flange 15 along which the top and bottom edges of the containers run, while being revolved along said semi-circular way. The semi-circular way being made in two parts permits of its being adjusted 95 to suit containers of different lengths.

16 (see Fig. 5) is a screwed jointing rod by means of which this adjustment is effected. 18 and 19 are brackets for supporting the semi-circular way 14. These brackets are attached by bolts 20 to a horizontal plate 17 supported on the lower end of pedestal 6. 21 is the receptacle for the labels 22, which labels are supported on plate 23, which in turn is carried on a vertical rack 24 which passes through and is free to move upward or downward in a slot in the plate 17.

25 is a counter-weight attached by rope 26 to a ratchet wheel in engagement with 110 said vertical rack 24. By this means the labels 22 in receptacle 21 are kept always

pressed tightly against the projections 27 (see Fig. 3) in the upper portion of said receptacle.

28 is a race at one end of the semi-circular way 14 into which the containers 9 are fed to be labeled, and 29 is another race at the other end for the delivery of the labeled containers.

30 (see Fig. 5) is a receptacle for gum situated at the feed end of the semi-circular way 14, and 31 is a pair of metal disks each carried on the end of a boss 32 (which bosses are movable laterally) on horizontal axle 33. These disks as shown in Fig. 5 revolve through the gum in receptacle 30. 34 is a receptacle for paste on the left of the label receptacle 21. At each end of the paste receptacle is a pulley wheel 35 around which passes a band or belt 36 composed of absorbent material, which band or belt is for the purpose of picking up and conveying paste to fasten the meeting edges of the label wrapped around the container in its journey along the semi-circular way 14.

25 Motion is imparted to the pulley wheels 35 and to the band or belt 36 by means of belt 37 from horizontal axle 3. To enable the gumming device to accommodate itself to containers of different diameters the gum receptacle 30 is supported on bracket 30^A and can be raised or lowered by manipulating set screws 30^B. The axle 33 carrying the metal disks 31 has a pulley wheel 35^A at one end, and said metal disks are caused to revolve 35 in the gum receptacle 30 by means of belt 38^A which engages with said pulley wheel 35^A, and with another pulley wheel on axle 3. The axle 33 and its appurtenant parts are carried in brackets 42, and are capable 40 of being raised or lowered to coincide with the raising or lowering of the gum receptacle 30, by manipulating set screws 43, 39 (Fig. 1) shows the slot in which said axle moves.

40 is a Bunsen burner beneath receptacle 45 30 to heat the gum therein when required. 41 is a rubber pad which is supported on brackets 42 attached to opposite sides of the semi-circular way 14, the upper part of said rubber pad projecting slightly above said 50 flanges as shown in Fig. 6 of the drawings.

The mode of operation is as follows. Motion having been given to the machine, the containers to be labeled are fed in any approved manner to the race 30, along which 55 they pass in succession to the semi-circular way 14, where the top and bottom edges thereof engage with the flanges of the wheels 1 and 2, and said containers being caused thereby to revolve along said semi-circular 60 way. As the containers pass over the metal

disks 31 sufficient gum is applied to their periphery to enable them as they pass over the receptacle 21 containing the labels 22 to pick up the end of one of said labels, and as said containers are further revolved along said 65 semi-circular way by the revolution of the wheels 1 and 2, each container has a label wrapped around it. The container in its further passage along said semi-circular way passes over the band or belt 36 slightly depressing it, and enabling paste to be applied to the meeting edges of the label to secure them together. As the containers pass upward to the race 29 they pass over the rubber pad 41 where the necessary compression 70 is given to insure the label being tightly affixed to the container. The labeled containers are then delivered to the race 29 at the other end of said semi-circular way, and from said race pass to any suitable receptacle.

What I claim is:—

1. In machines for labeling cylindrical containers and the like, the combination with a semi-circular way for the travel of the containers to be labeled, of a rotary device situated above and in alinement with said way, said device consisting of two wheels placed side by side upon a horizontal axle, and laterally adjustable thereon, the periphery of 85 each wheel constituting a series of steps, as and for the purpose described, and illustrated in the annexed drawings.

2. In machines of the class described, the combination with a semi-circular way for 95 the travel of the containers to be labeled, said way consisting of two side pieces, the lower edge of each side piece having an inwardly projecting flange for the top and bottom edges of the containers to run on, the 100 width between said side pieces being laterally adjustable, of a rotary device consisting of two wheels placed side by side upon a horizontal axle and laterally adjustable thereon, the periphery of each wheel constituting a series of steps, as and for the purpose described and illustrated in the annexed drawings.

3. In machines of the class described, the combination with the semi-circular way, 110 claimed in claim 2, of a receptacle for labels beneath said semi-circular way, means at one end thereof for applying gum to containers fed to said way, a rotary device for revolving said containers along said way, means 115 at the other end of said way for pasting the meeting edges of said labels together, and means for insuring the labels being tightly affixed to said containers.

ARTHUR MAYBREY NICHOLS.
